UNITED STATES PATENT OFFICE.

LUTHER L. KNOX, OF PITTSBURG, PENNSYLVANIA.

WATER-COOLED REVERSING-VALVE.

SPECIFICATION forming part of Letters Patent No. 708,718, dated September 9, 1902.

Application filed April 2, 1902. Serial No. 101,135. (No model.)

To all whom it may concern:

Be it known that I, LUTHER L. KNOX, of Pittsburgh, Allegheny county, Pennsylvania, have invented a new and useful Water-Cooled Reversing-Valve, of which the following is a full, clear, and exact description, reference being had to the accompanying drawings, forming part of this specification, in which—

Figure 1 is a vertical central section through a valve system embodying my invention. Fig. 2 is a vertical cross-section of the same. Fig. 3 is a top plan view, and Fig. 4 is a broken detail view, hereinafter referred to.

My invention relates to the reversing-valves used in connection with regenerative furnaces and is designed to provide a water-cooled-valve system for this purpose in which all the iron parts of the valves are protected by water and in which there are no valve-stems or mushroom-valves; also, to provide a valve system wherein the parts are open for inspection and can be easily reached for repair.

In the drawings, 2 and 3 represent the gas-ports leading from the gas-regenerators, and 4 is a stack-flue between them. The air-regenerative ports 5 and 6 are similarly located alongside the gas-ports, and between the air-ports is the stack-flue 7.

Referring to Fig. 1, 8 is an open-topped water-tank resting upon and extending longitudinally beyond the ports 2, 3, and 4. Over each of these ports a hole is provided in the tank with a surrounding flange 9. A rec-

tangular water-tank 10 rests within the tank 8 and contains a central box 11, having a closed top 12 below the level of the tank side, an open bottom portion inclosing two of the three ports. The tank 10 is narrower than tank 8, and its side and end edges dip within the water in tank 8. It is preferably provided with a set of baffle-plates 10', (shown in Fig. 4,) which give the water a tortuous course from the supply to the exit end and also serve to stiffen and strengthen the tank-shell. Within the end portions of the tank 10 are cylindrical flues 13, which are secured to recessed portions 14 of the tank-bottom, which are arranged to seat upon the flanges 9 of the gas-ports. The flue-sections 13 project upwardly within depending flues 15, which extend from a common transverse flue

16. The flues 15 and 16 are supported upon standards 17, having at their lower ends wheels 18, which travel upon the side flanges 55 of the tank 8. The gas-flue 19 leads into the flue 16 from a vertical gas-flue 20, supported upon the lower flue portion 21, which extends up through and is formed as a part of a tank 22. The tank 22 is carried upon wheels 23, 60 traveling upon the side flanges of a stationary tank 24, through which the gas-supply port 25 leads. To control the flow of gas from the flue 20 through the flue 19, I provide a cylindrical receptacle 26, having a 65 closed bottom with a depending annular flange 27, which dips into a water-sealing trough 28 within the vertical flue. A depending shell 29 extends down from the closed top 30 of the vertical flue into the water within the receptacle 26, thus allowing the valve to be moved vertically by means of its stem 31, while providing an efficient water-cooling and water-sealing system therefor.

The box 11 is provided with a damper 32, 75 which extends down into the water seal between the ports and projects upwardly through a pocket 33 in the top of the box. The pocket is surrounded by a water-sealing trough 34, into which the depending flanges 80 35, secured to the projecting upper end of the damper, depend. The damper may thus be adjusted to different heights, while its upward-projecting portion is constantly water-sealed, and the flow of gases to the stack is 85 thus controlled.

When the ports are in the position shown in Fig. 1, the damper 32 is lifted and the waste gases from the furnace pass upwardly through the flue 2 into the box 11, and thence 90 flow under the damper 32 into the stack-flue 4. At the same time gas is supplied through the flues 20, 19, 16, and 15 to the flue 3, and thence to the other gas-regenerator. To shift the valve from the position of Fig. 1 to the 95 reverse position, I pivot to each side of the tank 10 a series of links 36, whose lower ends are pivoted in bearings 37 on the side of the flues, and the double-acting motive cylinder 38, pivoted in bearings 39, is provided, the 100 piston-rod 40 of this cylinder having a loose connection 41 with one end of the tank 10. When fluid is admitted to force out the piston of this cylinder, the tank 13 will swing

upwardly and forwardly through an arc-shaped path into position where the ports 3 and 4 are connected through the inner box, while the port 2 is connected with the opposite down-flue 15. In this position the ports are all water-sealed, as before. During this movement of the tank 10 the flue sections 13 telescope within the flues 15, while the entire flue structure 15, 16, 19, and 20 travels longitudinally on the supporting-wheels without rising.

The valve system for the air-regenerators is similar to that above described, the parts being designated by similar numerals with the prime-mark. In this case the gas-connecting flue structure is dispensed with, and the ports 13' may be provided with vertically-movable covers or valves 42 to control the inlet of air to the air-regenerator.

The advantages of my invention will be obvious to those skilled in this art. The use of mushroom-valves is done away with, all the joints and metal parts are thoroughly water-cooled, and no valve-stems are used. The system is comparatively simple, the tanks are open for inspection, and all parts are easily accessible for repair.

Many changes may be made in the form and arrangement of the apparatus, which may be used for a single set of regenerators instead of a double set, as shown.

I claim—

1. A water-cooled reversing-valve comprising a stationary tank, ports extending up through the tank, a second tank resting within the stationary tank and containing ports extending up through it, and mechanism for shifting the second tank; substantially as described.

40 2. A water-cooled reversing-valve, comprising a tank, three ports extending up through the tank, a movable tank resting within the stationary tank, and containing a passage arranged to connect two of the ports, said movable tank having a third port leading up through it and arranged to connect with the third port, and mechanism for shifting the movable tank; substantially as described.

3. A water-cooled reversing-valve, comprising a tank, a series of at least three flanged ports extending upwardly through the tank, a movable tank resting within the stationary tank and having its bottom provided with an inverted box or channel arranged to connect two of the ports, a shell extending up through the movable tank and arranged to connect with another port, and mechanism for lifting the movable tank and shifting it longitudinally; substantially as described.

60 4. A water-cooled reversing-valve comprising a stationary tank having three flues extending upwardly through it, a movable tank supported in the stationary tank and containing a channel arranged to connect two of

the ports, vertical flue connections extending through the end portions of the movable tank, a gaseous supply flue connecting to the end flue portions of the tank, and mechanism for shifting the movable tank longitudinally; substantially as described.

5. A water-cooled reversing-valve comprising a stationary water-tank having flues extending upwardly through it, a movable water-containing tank resting within the stationary tank and containing a connecting-flue, and an end flue, pivotal links connected to the movable tank and mechanism for shifting said movable tank longitudinally; substantially as described.

6. A water-cooled reversing-valve comprising a stationary tank with ports opening through it, a movable tank resting therein with a connecting-flue, a water-sealed damper within said flue, and mechanism for shifting the movable tank; substantially as described.

7. A water-cooled reversing-gas-valve, consisting of vertically-extending gas-flues, a tank surrounding their upper ends, a movable tank within the stationary tank and having a port leading upwardly through it, said movable tank having a horizontal connecting-passage, and mechanism for shifting the movable tank horizontally in a vertical plane; substantially as described.

8. A vertical cylindrical supply-flue having an internal annular water seal, a vertically-movable tank within the flue having a depending flange within the water seal, an upper depending shell extending downwardly within the tank, and connections for moving the tank vertically; substantially as described.

9. A water-cooled reversing-valve comprising a tank, three ports extending up through the tank, a movable tank within the stationary tank and containing a passage arranged to connect two of the ports, said movable tank having end ports leading upwardly through it, mechanism for shifting the movable tank longitudinally in a vertical plane, and a gas-supply flue in constant connection with the end ports of said movable tank; substantially as described.

10. A water-cooled reversing-valve comprising a stationary tank with ports extending through it, a movable tank resting within the stationary tank and containing a connecting-flue, said movable tank having a third port extending upwardly through it, and mechanism for shifting the movable tank longitudinally in a vertical plane; substantially as described.

In testimony whereof I have hereunto set my hand.

L. L. KNOX.
